UNITED STATES PATENT OFFICE

IRENE GLENN, OF PORT WASHINGTON, NEW YORK

TEETHING DEVICE

Application filed April 20, 1932. Serial No. 606,454.

The present invention relates to teething devices.

The device is so constructed that it has a lip which is curved to fit the front portion 5 of the gums. This lip is carried by a handle and is arranged generally at a right angle to the handle. This arrangement permits of the lip being inserted within the mouth while the handle will stand longitudinally of the 10 body, so that the infant's arm may be low, comfortable, and more or less at rest. The curvature of the lip also prevents the use of the device as a pacifier. The device is in no sense a pacifier, but is designed for 15 use solely as a teething device, to provide a surface upon which the infant may bite to aid in cutting the teeth through the gum, and at the same time promote the ease and comfort of the infant, as much as possible.

20 The device is extremely simple and inexpensive to manufacture.

In the accompanying drawing, forming a part of this specification, in which like numerals are employed to designate like parts 25 throughout the same,

Figure 1 is a side elevation of a teething device embodying my invention,

Figure 2 is an elevation at a right angle to Figure 1,

30 Figure 3 is a plan view of the same.

In the drawing, wherein for the purpose of illustration is shown a preferred embodiment of my invention, the numeral 5 designates a straight handle or body portion.

35 Preferably formed integral with one end of the handle is a lip 6, which is curved in longitudinal section, and straight in transverse section. This curved lip extends laterally upon one side of the handle and has its longitudinal axis arranged generally at a right angle to the longitudinal axis of the handle.

40 The handle 5 is provided adjacent to its connection with the lip 6, with a bulbous shaped portion 7.

45 Formed integral with the opposite end of

the handle or body portion 5 is an eye 8, receiving therein a ring 9.

The entire device may be made of any suitably stiff or rigid material, such as celuloid, ivory, or the like.

50 The infant may grasp the handle 5 and insert the longitudinally curved lip 6 in the front portion of his mouth, between the front portions of the upper and lower gums. The lip 6 extends generally to the curvature of 55 the gums, and having its longitudinal axis disposed at generally a right angle to the longitudinal axis of the handle, the handle will lie close to the body of the infant, so that the arm holding the same may be low, 60 comfortable, and more or less supported, or at rest. With the device in this position, there is no danger of the handle being forced against the roof of the mouth of the infant, in the event of a fall, as may occur with 65 a teething device which is straight throughout its entire length. The longitudinal curvature of the lip 6 prevents such lip being used as a pacifier. The curved lip is useful principally in connection with the cutting 70 of the front teeth, and when it is desired that the device be used for cutting back teeth, the ring 9 may be inserted in the mouth of the infant.

75 It is to be understood that the form of my invention herewith shown and described is to be taken as the preferred example of the same, and that various changes in the shape, size and arrangement of parts may be resorted to without departing from the 80 spirit of the invention or the scope of the subjoined claims.

Having fully described my invention, what I claim is:

85 1. A teething device comprising a handle, and a lip curved in longitudinal section and substantially flat in transverse section carried by one end of the handle and projecting laterally beyond the handle, said lip having its longitudinal axis disposed generally at 90

a right angle to the longitudinal axis of the handle.

2. A teething device comprising a handle, and a lip curved in longitudinal section carried by one end of the handle and projecting laterally beyond the handle, said lip having its longitudinal axis arranged generally at a right angle to the longitudinal axis of the handle.

5 3. A teething device comprising a handle, and a lip secured to one end of the handle and having its longitudinal axis arranged generally at a right angle to the longitudinal axis of the handle.

10 15 In testimony whereof, I affix my signature.

IRENE GLENN.
